assor. to,

Hicks, Wolfe & Co. of same place.

Letters Patent No. 1346 Dated Nov. 13th, 1860

The schedule referred to in these Letters Patent and making part of the same.

To all whom it may concern:

Be it known that I, N. S. Vedder, of the City of Troy, in the County of Rensselaer and State of New York, have invented or produced a new and original Design for Cooking Stove Plates, called the La Fayette; and I do hereby declare that the following is a full and exact description of the same, reference being had to the annexed photographic drawing which makes a part of this Specification.

My ornamental design for cooking stove plates, consists of the compound moulding a, arranged along the periphery of each of the

rectangular doors or panels B, C, and D; the raised, oval, compound ornament e, placed on the middle of each of the doors or panels B, C; and the ornament f, in the angles, and the compound, raised, oval ornament g, disposed on the middle of the door, or panel D; all as shown by the annexed photographic drawing.

What I claim as my invention or production and desire to secure by Letters Patent, is the above described ornamental design for cooking stove plates.
